UNITED STATES PATENT OFFICE.

WILLIAM BARRY, OF NEW HAVEN, CONNECTICUT.

ROOF.

SPECIFICATION forming part of Letters Patent No. 247,596, dated September 27, 1881.

Application filed March 23, 1881. (No model.)

To all whom it may concern:

Be it known that I, WILLIAM BARRY, of New Haven, in the county of New Haven and State of Connecticut, have invented a new and 5 useful Improvement in Roofs, of which the following is a description.

This invention relates to a certain improvement in roofs, its object being to readily drain off the storm-waters; and it consist in providing the side inclined stones or material of the roof, near their upper ends, each with two inclined grooves meeting at their lower points of inclination about midway the width of the stone or material, and having thereat an outlet, all arranged under the ridge stone or piece, 15 substantially as hereinafter more fully set forth and claimed.

In the accompanying drawings, Figure 1 is a perspective view, showing my improvement 20 at the right of the joint, and Figs. 2, 3, 4, and 5 are details and a section of the joint.

To enable others skilled in the art to which my improvement appertains to make and use the same, I will describe it.

25 A indicates a stone forming a part of the roof of a vault. One-half of its overlapping part a is cut away in such a manner that the overlapping surface is inclined, and so that the cut surfaces form an acute angle. In the inclined overlapping part the groove x is cut.

B represents another stone forming a part of the roof, and has one-half of its overlapping part b cut away in such a manner that the overlapping surface is inclined, and so that 30 the cut surfaces make an acute angle. These overlapping parts a and b fit together, and the surfaces of the stones form an even surface. In the upper part of the stones are cut the

grooves m n. Two of these grooves are made in each stone and inclined downward, meeting 40 at their lower points of inclination about midway the width of the stone, where they are provided with an outlet, as at m', for draining off the water received into the grooves or gutters m n, dripping into the latter between the 45 joints of the ridge piece or pieces.

A groove, o, uniting the inclined grooves or gutters at a point above their conjunction, may be provided for aiding drainage, if desired; but it is not essential.

The stones C, Figs. 1 and 2, form the ridge of the vault, fit on the stones forming the sides of the roof, and are united by joints made after the form of joint uniting the inclined side pieces. The aforesaid form of joint is old, its 55 function, as is well understood, being to drain any water passing down between the stones into the acute angles, which will run it off, and to carry off by the grooves x any water rising by capillary attraction or driven up by the 60 wind. I therefore lay no claim to such construction.

I claim and desire to secure by Letters Patent—

In a roof, the inclined side stones or pieces 65 having near their upper ends and under the ridge stone or piece each two inclined grooves or gutters, m n, meeting at their lower points of inclination and provided thereat with an outlet, m', substantially as and for the purpose set forth.

WILLIAM BARRY.
